UNITED STATES PATENT OFFICE.

FREDERICK C. OVERBURY, OF HILLSDALE, NEW JERSEY, ASSIGNEE, BY MESNE ASSIGNMENTS, TO THE FLINTKOTE COMPANY, OF BOSTON, MASSACHUSETTS, A CORPORATION OF MASSACHUSETTS.

MACHINE FOR MAKING ROOFING ELEMENTS.

1,317,384.

Specification of Letters Patent. Patented Sept. 30, 1919.

Application filed December 27, 1915. Serial No. 68,660.

To all whom it may concern:

Be it known that I, FREDERICK C. OVERBURY, a citizen of the United States, residing at Hillsdale, in the county of Bergen and State of New Jersey, have invented new and useful Improvements in Machines for Making Roofing Elements, of which the following is a specification.

This invention has relation to machines for making roofing elements, and has for its object to provide a machine for making what I term shingle strips, *i. e.*, strips of sheet roofing material provided with tabs or projections of any desired configuration, which, when the strips are laid in overlapping relation, present the appearance of separate shingles or tiles.

On the accompanying drawings,—

Figure 1 represents in plan view a machine embodying the invention;

Fig. 2 represents a longitudinal section through the machine on the line 2—2 of Fig. 1;

Fig. 3 shows a sheet of roofing material and a shingle strip which has been severed therefrom; and

Figs. 4, 5 and 6 are sectional views illustrating the feeding and the severing of the sheet into strips.

The machine is particularly adapted for operation upon sheet roofing material comprising one or more layers of felt or analogous fibrous material saturated or impregnated with a suitable waterproofing compound such as asphalt, pitch or the like, and coated with a relatively hard pitch or asphalt, and surfaced if desired, with a layer of crushed mineral material or grit more or less embedded in the coating before it sets or hardens.

Referring to the drawings, the machine as shown may conveniently comprise side standards 10, 11, suitably connected and braced and of any suitable design. At one end the machine has a pair of feed rolls 12, 13, connected together by the gears 14, 15, to one of which power is applied to cause their rotation as will presently be explained in detail. The rolls extend across the machine and are of sufficient width for the sheet to be fed thereby.

At the other end of the machine are the coacting cutting rolls or cylinders, of which

that at 16 is a bed roll, and may be formed of steel or equivalent hard material, and that at 17 carries the cutting blades. The roll 17 is milled longitudinally on its periphery to provide grooves to receive cutting blades 18, for coöperation with the bed roll. The shape of the blades depends upon the desired contour of the tabs or projections on the shingle strips. For example, each of the blades 18 is shown as zigzag, so that, when the strip *a* is severed it will have along its edge a series of angular projections *b*. The two blades 18 may be the same, or they may vary in shape, so that the tab on the two longitudinal edges of each strip will have a different contour. These blades are inserted and rigidly held in the grooves formed in the roll 17, and their edges are concentric with said roll, so as tangentially to engage the bed roll 16.

The roll 16 not only coöperates with the cutters in severing the strips, but it also serves in feeding the end of the sheet *c* of roofing material. To this end, I employ an additional feed roll 19, located in the rear of the bed roll 16, in such close proximity thereto as to cause them to grip the end of the sheet. The roll 19 and the rolls 12, 13, 16 and 17 are all journaled in suitable bearings on the side frames 10 and 11. The axis of the roll 19 is slightly below a plane tangential to the rolls 15 and 16, so that the sheet is compelled to travel a somewhat tortuous path in passing from the feed rolls to the cutting rolls. I employ therefore a table 20 extending from one side frame to the other, the front end of which is bent downwardly and forwardly to guide the sheet to the under side of the feed roll 19.

In operation, as shown in Figs. 4, 5 and 6, the end of the sheet is engaged by the rolls 16 and 19, and is fed thereby to position to be engaged by the cutters 18. As one cutter in its revolution cuts off a strip from the extremity of the sheet, the end of said sheet remains in the grip of the feed and bed rolls and is fed to position to be engaged by the next cutter.

The rolls 12, 13, 16 and 19, and the cutters 18, all travel at the same peripheral speed and may be connected by any suitable gearing to secure this result. For example, I may employ the following train of power-transmitting mechanism:—a main shaft 220

driven by a belt 21 and pulley 22, a gear 23 on said shaft, a gear 24 on the bed roll shaft intermeshing with gear 23, a gear 25 on the cutter roll shaft intermeshing with gear 24, 5 a gear 26 on the shaft of the feed roll 19 driven by gear 24, and idler gears 27, 28, driven by gear 26 and driving gear 15 on the roll 13. The gear 27 is secured on a shaft 29 on the other end of which is a 10 sprocket wheel 30 for transmitting power by the chain 31 to a sprocket 32 on a drum shaft 33. The shaft 33 and a parallel shaft 34, on a lower plane, operate an inclined endless belt 35, located to receive and carry 15 away from the machine the severed shingle strips.

The sheet to be cut into strips may be drawn directly from the coating rolls; but, if in roll form, the roll of material as at 20 d may be journaled on a frame 40 as shown in Fig. 2.

It will be observed that each cutter 18 is continuous from end to end, so as completely to sever the strip from the end of the sheet, 25 said cutter being in total length not less than the width of the sheet. I refer to each blade as a "zigzag" blade to distinguish it from one which would cut the sheet on a straight or unbroken transverse line, meaning to include thereby any transversely arranged 30 blade which will leave tabs or projections on the longitudinal edge of the strip.

Having thus explained the nature of my said invention and described a way of making and using the same, although without attempting to set forth all of the forms in

which it may be made or all of the modes of its use, what I claim is:

1. A machine for cutting shingle strips having tabs or projections from a sheet of 40 roofing material, comprising a bed roll, a co-operating cutting roll, said cutting roll having a zigzag blade extending longitudinally of the periphery thereof, so as to sever the sheet transversely from edge to edge thereof and form the described strip, a feed roll 45 co-operating with said bed roll for feeding the sheet, a pair of feed rolls, and a table between the pair of feed rolls and the said feed roll and co-operating bed roll for guiding the sheet to said feed roll and bed roll. 50

2. A machine for cutting shingle strips having tabs or projections from a sheet of roofing material, comprising a pair of feed rolls and a pair of cutting rolls, the axes of 55 the feed rolls being in a vertical plane parallel to the plane of the axes of the cutting rolls, the cutting rolls comprising a smooth cylindrical bed roll and a cylinder having one or more zigzag blades extending from 60 end to end thereof, in combination with a supplemental feed roll consisting of a smooth cylinder arranged to co-operate with said bed roll and having its axis located in a plane below and parallel to a plane tangential to the first-mentioned feed rolls and cutting rolls, and a table arranged to guide the sheet from the feed rolls to the supplemental feed roll. 65

In testimony whereof I have affixed my 70 signature.

FREDERICK C. OVERBURY.
